UNITED STATES PATENT OFFICE

102,861

DESIGN FOR A FLEXIBLE CIGARETTE CASE

Edwin A. Lemire, Providence, R. I.

Application September 30, 1936, Serial No. 65,082

Term of patent 7 years

To all whom it may concern:

Be it known that I, Edwin A. Lemire, a citizen of the United States, residing at Providence, in the county of Providence and State of Rhode Island, have invented a new, original, and ornamental Design for Flexible Cigarette Cases, of which the following is a specification, reference being had to the accompanying drawing, forming part thereof.

Fig. 1 is a perspective view of the flexible cigarette case in a partially flexed position, showing my new design.

Fig. 2 is a side elevational view of the same, and,

Fig. 3 is a detail sectional view, taken substantially along the line 3—3 of Fig. 1.

The principal characteristics of my design are the plurality of connected sections movable relative to each other and having the intermediate sections of substantially rectangular cross section in outline with substantially plane lateral surfaces and curved end surfaces forming in the closed position of the parts substantially plane lateral surfaces merging substantially uniformly into curved edge surfaces.

I claim:—

The ornamental design for a flexible cigarette case, substantially as shown and described.

EDWIN A. LEMIRE.
